UNITED STATES PATENT OFFICE.

WILLIAM ALEXANDER FRASER, OF GEORGETOWN, ONTARIO, CANADA.

FLUSHING-TANK.

1,047,510.

Specification of Letters Patent. Patented Dec. 17, 1912.

Application filed November 8, 1911. Serial No. 659,153.

To all whom it may concern:

Be it known that I, WILLIAM ALEXANDER FRASER, of the town of Georgetown, in the county of Halton, in the Province of Ontario, Canada, have invented certain new and useful Improvements in Flushing-Tanks, of which the following is the specification.

My invention relates to improvements in 10 flushing tanks, and the object of the invention is to devise a flushing tank and water controlling mechanism therefor, which will entirely dispense with the intake valve commonly known as the ball float valve.

15 A further object is to make the tank compact in form and size, and independent of variation in pressure.

A still further object is to provide a sanitary antiseptic device, which will insure the 20 reflush water in the bowl being antiseptic.

My invention consists of a tank having a main water supply pipe, a main flush pipe to the bowl, a cylindrical float provided with a suitable valve designed to rest upon a seat 25 at the top of the flush pipe, a controlling lever, and a controlling disk designed to contact with the valve, an air outlet at the top of the tank provided with a cylindrical valve and extending at the bottom into a 30 flow pipe, a valve communicating with the interior of the tank and to the air valve designed to control the water passing to the bowl to reflush it, a casing located intermediate of the length of the air pipe and containing a suitable antiseptic substance 35 designed to disinfect and render odorless the reflush water as it passes to the bowl, the parts being otherwise constructed and arranged as hereinafter more particularly explained.

Figure 1, is a vertical section through my flushing tank. Fig. 2, is a similar view showing a slight modification. Fig. 3, is a perspective detail partially in section showing the main float valve. Fig. 4, is a perspective view mostly in section showing the air pipe valve. Fig. 5, is a detail showing the valve for controlling the re-flush water. Fig. 6, is a perspective detail of the valve support shown in Fig. 5. Fig. 7, is an enlarged view showing the antiseptic casing on the air pipe.

In the drawings like letters of reference indicate corresponding parts in each figure.

55 A is the tank, which is closed both at the bottom and top being provided with a

threaded orifice A' at the top and a plain orifice A² at the bottom.

B is the float cage, which has side guide-bars B' and a top B².

60 C is the top portion of the main flushing pipe, which is provided with a flange C' whereby it is secured to the bottom of the tank, a spider C² with a central orifice C³ and a seat C⁴ at the top provided with an annular shoulder C⁵ against which the bottom edge of the cage abuts.

65 D is the float, which is preferably cylindrical in form and has a cone-frustum shaped bottom D' to which is secured the 70 disk valve E preferably made of rubber and having an annular space E² to make it more flexible and press more tightly on the seat C⁴. The disk valve E is secured in place by a rod F having a flat head F', such rod extending upwardly through the cylindrical float D and being held at the top by a nut and washer. The flush pipe C is provided with a lateral off-set portion C⁶ in which is 75 fulcrumed the arm G on the pin G', the outer end of which has connected to it the operating lever arm G². The inner end of the arm G has a slotted connection to a rod H, which extends through the hole C³ in the spider C² and has secured to the upper end 80 a spider H'. The 85

I is the main water supply pipe. This pipe I, I provide with a globe valve I' having an indicating pointer I² whereby the globe valve may be turned any desired distance to indicating points I³, so as to make the orifice through the valve larger or smaller according to the quickness with which it is designed to fill the tank. This valve is provided, where my flushing tank is 90 arranged in connection with a reservoir especially used in railway coaches.

The threaded orifice A' at the top of the tank A carries a valve casing J having a bottom spider J' and a top elbow like orifice J².

100 J³ is a cylindrical float normally supported on the spider J' and provided at the top with a ring J⁴ attached to or forming part of a spider-like support J⁵, which 105 may form part of the cylindrical casing J³. On the top of the ring J⁴ is arranged a valve J⁶ preferably of rubber.

110 The casing J is provided at the top with a nipple J⁷ and to this is connected a pipe K, which extends either inside or outside of the tank A. I have shown it on the

inside. At the bottom of the pipe K outside the tank I provide a supplemental separable casing L, which is threaded at the top on to the pipe K and is provided with 5 a flange L' by which the upper portion is screwed on to the exteriorly threaded top of the lower portion. The casing provides an enlargement L² between the lower end of the pipe and the nipple C³ forming part 10 of the top portion C of the flush pipe.

Disks or washers M of any convenient size are utilized in the enlargement L² and these disks are made of any antiseptic or disinfecting substance and are preferably 15 provided with an orifice M', and are of less diameter than the diameter of the enlargement. By unscrewing the top portion of the casing L the washers may be placed in position.

20 K' is an elbow-like extension of the pipe K located inside of the tank A and provided with a recessed enlargement K².

N is a valve having a spiderlike bottom N' and a ring-top N² surmounted by a disk 25 valve N³ and held on the top of a spider K³ at the bottom of the enlargement K².

In Fig. 2, I also show the style of valve used in connection with the main float, which I use where the tank is under pressure, such as from a city main. In this 30 form I make the disk valve D² with a central orifice D³, the float D⁴ carrying the central rod F², which extends through the float to a disk F³ having a central opening 35 F⁴. Upon the depression of the lever G² and consequently the raising of the rod H the float is first raised without raising the 40 disk valve and the water under pressure passes through the orifice D³ and orifice F⁴. This serves to relieve the pressure on the disk valve D², so that when the disk F³ reaches it the valve being relieved of pressure 45 may be readily removed from its seat and allow of the water to pass underneath the same.

Having now described the principal parts involved in my invention I shall briefly describe its operation and utility.

Referring to Fig. 1, the water passes 50 through the pipe I into the tank and rises in the tank. The displaced air in the meantime passes outwardly around the valve J³ and through the pipe K and down into the flushing pipe C. This passing of the air 55 through the pipe C continues until the water has risen sufficiently high in the tank to raise the valve J³ and close the orifice by means of the valve J⁶. During this period the pressure of the water in the tank is not

at first sufficient to close the valve N³, so 60 that the water coming into the tank will partially pass through the elbow K' and will trickle down through the pipe K into the flush pipe C permeating on its way the anti-septic disks M and carrying with it a certain amount of disinfecting fluid, which 65 passes into the bowl in the closet, and, therefore, will keep it sanitary. When the water has reached a sufficient height the pressure on the valve N³ will cause it to close and 70 stop any more flush water passing. It will, of course, be understood that the orifice in the elbow K' is comparatively much smaller than the orifice in the pipe I from 75 which the pipe is fed.

It will be seen from this description that by the means, which I employ for operating my float and valve, that it is not necessary to have any packed joints, or separate opening to the tank, which minimizes the liability of leakage. It will also be seen from this description that I am enabled to fill the tank very quickly, and without any air pressure on the water as it passes to the tank as the air is drawn off as the water rises. 85 Another advantage in my invention is that the operating lever is always restored to normal by the fall of the valve on to its seat.

What I claim as my invention is: 90

1. The combination with the tank and flushing pipe, of an air pipe, extending within the tank from the top of the tank down to the flushing pipe, and a valve for closing the air pipe at the top of the tank upon the 95 rising of the water in the tank, an elbow on the air pipe located intermediate of its length within the tank provided with an orifice, an enlargement formed on said elbow, a valve located within said enlargement and beneath said orifice, a second enlargement formed on the lower end of said air pipe adapted to receive antiseptic material. 100

2. The combination with the tank and flushing pipe and inlet pipe, of an air pipe extending from the tank to the flushing pipe, of a conduit leading to the air pipe and provided with a suitable valve, said air pipe having an enlargement at its lower end 110 adapted to receive disinfectant material, said enlargement comprising two separable sections.

WILLIAM ALEXANDER FRASER.
